US00D925928S

(12) **United States Design Patent** (10) **Patent No.:** **US D925,928 S**
Yang et al. (45) **Date of Patent:** **** Jul. 27, 2021**

(54) **VANITY MIRROR**

- (71) Applicant: **simplehuman, LLC**, Torrance, CA (US)
- (72) Inventors: **Frank Yang**, Rancho Palos Verdes, CA (US); **Tzu-Hao Wei**, Hacienda Heights, CA (US); **Daniel Ballou**, Long Beach, CA (US)
- (73) Assignee: **simplehuman, LLC**, Torrance, CA (US)
- (**) Term: **15 Years**
- (21) Appl. No.: **29/682,152**
- (22) Filed: **Mar. 1, 2019**
- (51) LOC (13) Cl. **06-07**
- (52) U.S. Cl. **USPC D6/309; D6/312**
- (58) **Field of Classification Search**
 USPC D6/300, 301, 308, 309, 310, 312
 CPC A47G 1/00; A47G 1/0633; A47G 1/0622;
 A47G 1/04; A47G 2200/08; A47G 2200/085; A45D 42/20; F21V 33/004

(57) **CLAIM**

The ornamental design for a vanity mirror, as shown and described.

DESCRIPTION

FIG. 1 is a top, front, left-side perspective view of a vanity mirror embodying our design in a first state;

FIG. 2 is a top, rear, right-side perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and

FIG. 8 is a bottom plan view thereof.

FIG. 9 is a top, front, left-side perspective view of the vanity mirror embodying our design in a second state;

FIG. 10 is a top, rear, right-side perspective view thereof;

FIG. 11 is a front elevation view thereof;

FIG. 12 is a rear elevation view thereof;

FIG. 13 is a right-side elevation view thereof;

FIG. 14 is a left-side elevation view thereof;

FIG. 15 is a top plan view thereof; and,

FIG. 16 is a bottom plan view thereof.

All features in broken line form no part of the claimed subject matter.

1 Claim, 12 Drawing Sheets
